CLAIM

The ornamental design for a roundabout for children's playground as shown and described.

DESCRIPTION

FIG. 1 is a perspective view of a roundabout for children's playground.

FIG. 2 is a front side elevation view thereof.

FIG. 3 is a back side elevation view thereof.

FIG. 4 is a left side elevation view thereof, the right side elevation view being identical.

FIG. 5 is a top view thereof; and,

FIG. 6 is a bottom view thereof.

The features shown in broken lines in the drawing depict portions of the roundabout for children's playground only and form no part of the claimed design.

1 Claim, 6 Drawing Sheets
